APPARATUS FOR DRILLING WELLS

Application filed April 30, 1925. Serial No. 26,880.

This invention relates to well and other earth drilling apparatus and refers particularly to the type of apparatus employed in the rotary method of drilling deep wells such as oil wells.

In the rotary method of drilling wells as generally carried out, the hole is made by the cutting action of a bit attached to and rotated by a vertical pipe extending to the surface of the ground. Such a pipe is known 10 in the art as a drill stem. The drill stem is swively sustained at its upper end by a hoist consisting of a block and tackle connected to a hoisting drum, which drum, with its associated driving and regulating appliances, is known in the art as the draw- 15 works. By means of the drawworks, the percentage of the weight of the drill stem which is permitted to rest upon the drill bit may be controlled. During drilling 20 operations the drilling bit is rotated by the rotation of the entire drill stem which in turn is driven by a so-called rotary table disposed at the surface of the ground.

With such general type of rotary drilling 25 apparatus, when manually operated, the control of the power applied to the rotary table for rotating the drill stem is independent of the means utilized for controlling the draw- 30 works to regulate the percentage of the weight of the drill stem permitted to rest upon the drill bit. With such an apparatus, in the normal drilling of a well the rotating torque upon the drill stem is furnished by a 35 source of power of some character which is normally allowed to function uncontrolled by the operator and governed only by the resistance encountered to the rotation of the drill stem and bit. The operator endeavors 40 to maintain upon the drill stem the correct drilling torque by so manipulating the hoisting drum as to continually compensate for the deepening of the hole and to constantly impose that correct feed pressure upon the 45 bit which will maintain an efficient, safe drilling rate. It is impossible, however, for the operator, due to the variations encountered in drilling, to maintain in this way such control over the drilling apparatus as 50 will establish a uniform drilling rate or uni-

form torque loads or other strains upon the drilling apparatus. Whenever fluctuation is made from the correct drilling conditions, the wear and damage upon the bit is greatly increased, danger of damaging the drilling 55 apparatus is also increased, and the quantity and quality of hole made is decreased.

Certain automatic drilling apparatus have been designed for the drilling of deep oil wells intended to provide mechanism adapted to displace the manual control of the feeding pressure applied to the bit and to substitute in lieu thereof automatic control of all the forces applied to the drill stem so as to maintain correct and optimum drilling 60 conditions. One of the principal difficulties with such automatic drilling machines as have been heretofore devised is that they are unsuited for use in connection with the present type of drilling apparatus. In drilling 65 a deep well, such as an oil well, there is a great deal of apparatus in addition or supplemental to that employed for drilling which must be available for carrying out the operations auxiliary thereto. This auxiliary 70 apparatus must be mounted in the same well rig and preferably should be drivable by the same prime mover and must be free to operate without interference from the automatic devices controlling actual drilling. 75 These prior devised automatic drilling machines have been unsuited and unsatisfactory for practical use for the reason that they cannot be employed without impracticable displacement or extensive readaptation of 80 the necessary auxiliary drilling apparatus. 85

It is the primary object of the present invention to provide an automatic drilling apparatus for the drilling of wells which is adapted for practical or commercial use, and which can be simply and easily installed without expensive changes in the apparatus at present in use in the usual well drilling rig.

By this invention we not only provide such an automatic drilling apparatus as is utilizable for well drilling while still permitting the efficient performance and efficient control of the necessary auxiliary apparatus of a well rig, but we also provide an automatic driving device which can be installed in the

present type of well drilling rig with but slight modifications and additions thereto. We thus are able to convert the well drilling rig now in use to an automatic well drilling apparatus.

In carrying out the objects of the present invention, we preferably utilize a differential gearing for connecting the prime mover of the well drilling apparatus to the rotary table 10 and to the drawworks so that the operations of the drawworks and rotary table are automatically controlled. The differential employed is so constructed that it is compact in size and readily inserted between the prime mover and hoisting drum of the present type drilling rig. We also employ in this invention such a type or form of differential gearing between the source of power and rotary table and hoisting mechanism as can be connected thereto by the usual form of flexible chain drives.

In order that the differential provided may be adapted to be assembled in a compact form and, when so assembled, control the hoisting drum and rotary table without extensive modifications therein and preferably through the usual form of chain drives, we provide a differential in which one of the driving shafts is adapted to act also as a main mounting or supporting shaft for the entire differential and the other driving shaft we construct of quill form revolvable on the said supporting shaft and thus provide both a compact and self-contained form of differential and also one adapted to withstand the heavy stresses of the drilling operations.

The invention and various further features, objects, and advantages thereof will best be understood from a description of a preferred form or example of well drilling apparatus embodying the present invention, for which purpose reference is made to the accompanying drawings, illustrating one example of a well drilling apparatus embodying the invention.

In the drawings:

Fig. 1 is an elevation of a well drilling apparatus embodying our invention, the usual apparatus employed in the operations auxiliary to drilling not being illustrated, as they may be of standard construction, and it will be recognized by those skilled in the art that the drilling apparatus herein illustrated does not interfere or hinder the employment of such standard auxiliary apparatus.

Fig. 2 is an enlarged plan view of the apparatus illustrated in Fig. 1, with the derrick removed.

Fig. 3 is a rear elevation of the apparatus, looking at the rear of the differential from the prime mover.

Fig. 4 is a side elevation of the apparatus shown in Fig. 3.

Fig. 5 is an enlarged end view of the differential and its mounting.

Figs. 6 and 7 together represent a complete longitudinal section of the differential.

Fig. 8 is a transverse section on the line 8-8 of Fig. 6.

Fig. 9 is a transverse section on the line 9-9 of Fig. 6.

Referring to the drawings, the well drilling apparatus there illustrated comprises the customary well derrick 2 upon a suitable foundation 3. The derrick 2 supports at its top a crown block 4 for the reception of various lines 6 of a tackle and falls. 5 indicates a traveling block supported upon the lines 6 and connected thereby over the crown block 4 to a hoisting drum 7 forming a part of the usual drawworks. The traveling block 5 swivelly supports a drill stem 8 which carries at its lower end a drilling bit 9. Thus by control of the drum 7 of the drawworks, the percentage of the weight of the drill stem permitted to rest upon the drilling bit 9 may be controlled during drilling operations. The drill stem 8 is adapted to be rotated in use by a rotary table 10 of any preferred or customary construction. In accordance with the principles of this invention the drilling machine derives its power from a prime mover 11 which may be of any type such as a steam engine, internal combustion engine, or electrical motor. Preferably, this prime mover 11 is placed rearwardly of the drum 7 of the drawworks from the rotary table 10 in order that all of the drilling apparatus may be disposed at one side of the well rig 2, leaving the remainder of the rig free for the installment of auxiliary apparatus and for the performance of other auxiliary operations.

The prime mover 11 is connected by suitable means such as a chain drive 12 to a differential 13, from which the force or power from the prime mover 11 is transferred to the rotary table 10 and hoisting drum 7 in such manner as to automatically operate those parts. The differential 13 is of special construction so that it is adapted to withstand the heavy drilling stresses and is in a compact and self-contained form and can be conveniently disposed between the hoisting drum 7 and the prime mover 11 with its driving shafts parallel to the axis of the draw-works. It can be made as a unit assembly carrying all its parts and elements upon a single base so that it can be installed as a unit in the drilling rig without requiring assemblage when installed.

The construction of the differential is best illustrated in Figs. 6 and 7, the differential being provided with a main shaft 14 supported at or near its ends by bearing blocks 15 and 16 respectively mounted upon I-beams 17 affixed to the floor timbers of the derrick 2. This main shaft 14 serves to support the en-

tire differential on said bearings 15 and 16 and thus acts as a supporting shaft for other operating parts of the differential and in addition thereto is itself one of the driving shafts of the differential. The shaft 14 carries a beveled gear 18 having a hub 19 acting as a collar by which the beveled gear 18 is rigidly held to the shaft 14 by a key 20.

21 indicates a second driving shaft of the differential, which driving shaft is of quill form and is mounted on the main shaft 14 by roller bearings 22 and 23 at its respective ends. These bearings are held spaced apart by a sleeve 24 therebetween. The inner end of bearing 22 abuts the end of the hub 19 of the beveled gear 18 and the outer end of the bearing 23 engages an inturned flange 24^a on the quill shaft 21 and the bearing is thus held from outward movement. The quill driving shaft 21 is provided with an enlarged bore 26 between the roller bearings 22 and 23 in order to form a lubricant reservoir, as will hereinafter be pointed out. As later pointed out in operation the shaft 21 rotates rapidly relative to the supporting shaft 14 and the roller bearings 22 and 23 are preferred to withstand the stresses developed at high speed.

The inner end of the quill driving shaft 21 is keyed to a beveled gear 27 by which it is driven. The gears 18 and 27 mesh with a pinion gear 28. One or more of such pinion gears 28 may be provided meshing with the beveled gears 18 and 27, the pinion gear or gears 28 being mounted upon a spider 29 which is secured to a gear housing or case 30. The pinion gears 28 are provided with bronze or roller radial and thrust bearings 28^a and 29^a respectively. The gear housing or case 30 provides annular chambers 31 and 32 respectively at both sides of the gearing for the reception of lubricant, from which chamber it is conveyed through suitable holes and channels to all other parts of the differential and to the reservoir 26 provided by the quill shaft 21. One end of the housing or case 30 is provided with a hub 33 mounted by a bronze or roller bearing on the main supporting shaft 14. The hub 33 also serves to mount a sprocket wheel 34 keyed thereon as indicated at 35, and bolted to the sides of the gearing housing or case 30. The sprocket wheel 34 is driven by the sprocket chain 12 from the prime mover 11.

The other end of the gear housing or case 30 is provided with a hub 36 mounted through bronze or roller bearings 37 upon the hub of the beveled gear 27 carried by the quill shaft 21; said hub 36 also engages a bronze or roller thrust bearing 38 engaging the back face of the beveled gear 27 from which the end thrust of the beveled gear 27 and quill shaft 21 rigid therewith is received.

The end of the quill shaft 21 is provided with a clutch face adapted to be engaged by the clutch face of a quill clutch 41 mounted on

the main shaft 14 and keyed thereto. This clutch in operation may be utilized to lock the quill shaft 21 to the main shaft 14; the differential gearing is then frozen and the whole differential operates as a single rigid shaft. 70

Rotatably mounted on the quill shaft 21 near its upper end is a sprocket wheel 42. This sprocket wheel 42 at its inner end has a clutch face engageable with the clutch face of a clutch 45; the clutch 45 abuts the end of the gear housing 30 and is slidably keyed upon the quill shaft 21 as indicated at 46. At the opposite side of the gearing, the main shaft 14 rotatably mounts two sprocket wheels 47 and 48 respectively of different sizes and having clutch faces adapted to be selectively engaged by clutch faces of a double clutch 49 disposed therebetween and slidably keyed on the main shaft 14. 75 80

The gear housing 30 may have its chambers 31 and 32 filled with lubricant through a plug 50. From the chambers 31 and 32 the entire bearings for the differential are lubricated, the lubricant passing from the chamber 31 through holes 51 to the bearing 37, through holes 51^a to bearings 28^a and 29^a, and between the gears through channel 52 and radial ducts 53 in the quill shaft 21 to the chamber 26 formed by the enlarged bore of the quill shaft, from which it may pass to the high-speed roller bearings of such shaft. In this manner all of the lubricant can be supplied from one point to all the bearings of the differential. 85 90

Preferably, means are provided on each of the driving shafts 14 and 21 to impose an artificial restraint to their rotation when desired. The preferred form of such means are the brake drums 54 and 55, for the shafts 14 and 21 respectively. The brake drum 54 is keyed on the shaft 14 beyond the sprocket wheels 47 and 48 and the brake drum 55 is rigidly secured to the sprocket wheel 42 to be driven by the quill shaft 21. 100 105 110

In order that such differential may be employed in driving the rotary table and hoisting drum without requiring material changes in the present drilling apparatus, or the addition of further apparatus for attaching the differential thereto, use is made of the customary line shaft 56 of the draw-works in connecting the differential to the rotary table 10 and the hoisting drum. For this purpose, said line shaft is made to revolvably mount a collar 57 carrying two sprocket wheels 58 and 59. A chain 60 drives the sprocket wheel 58 from the sprocket wheel 42 driven by the quill shaft 21 of the differential and the sprocket wheel 59 carries a chain 61 driving the rotary table 10. In performing this function, the customary line shaft is utilized merely as an axle for the sprockets 58 and 59 of the rotary table drive. The line shaft 56 also serves as 115 120 125

a countershaft between the differential 13 and hoisting drum 7 permitting a plurality of changes in the ratios of the relative speeds of the main shaft 14 and the drum 7. For this purpose, the sprocket wheels 47 and 48 which are adapted to be selectively driven by the main shaft 14 drive sprockets 64 and 65 on the line shaft 56 by means of chains 62 and 63, said sprocket wheels 64 and 65, being indicated as rigid with the line shaft 56. The connections between the line shaft 56 and hoisting drum 7 are the usual selective chain drives therebetween. In the ordinary drawworks there are provided two or more selective chain drives between the line shaft and drum, of which 66 and 67 respectively indicate different drives and their respective chains, sprockets and clutches. The line shaft 56 is indicated as disposed, as usual, with its axis parallel to the axis of the drum 7 of the drawworks and disposed thereabove.

The differential 13 thus described is of compact form and so constructed as to have both its driving connections directly through the medium of the customary line shaft, and is thus adapted to be disposed close to the drawworks, and with its axis parallel with the axes of the line shaft and drum. Thereby a compact automatic well drilling controlling mechanism is provided which can be installed or embodied in the usual type of well drilling apparatus now in use simply by bodily inserting the self-contained differential and associated parts between the ordinary prime mover and drawworks and the placing of a few additional sprocket wheels and chain drives on the line shaft.

The different clutches of the apparatus are preferably connected so that they may be operated at the common operating point of the drilling apparatus located at the right hand end as usual of the drawworks when facing the rotary table. For this purpose, one of the inner posts of the derrick mounts a lever control locking plate 80 having ways and grooves therein for locking levers 81, 82 and 83 in their different proper operating positions, the levers 81, 82 and 83 being employed to control the clutches of the differential. The lever 81 is connected by a rocker arm 84 and reach rod 85 to a yoke 86 controlling the double clutch 49 which selectively engages sprocket wheels 47 and 48. The lever 82 operates through rocker arms 87, reach rod 88 and yoke 89 to control the quill clutch 41 utilized in locking the quill shaft 21 to the main shaft 14 when it is desired to operate the differential as one rigid shaft. The lever 83 is connected by rocker arm 90, reach rod 91, and yoke 92 to clutch 45 which engages the sprocket wheel 42 which drives the rotary table 10.

The clutches on the hoisting drum 7 of the drawworks are operated as usual by foot levers 93 and 94 of standard construction dis-

posed under the lever control locking plate so that the entire control apparatus is centered at the customary place from which all drilling operations are conventionally controlled. The drums 54 and 55 also have operating handles 95 extending to the common control position where they may be manually operated at will to apply progressive resistance to the rotation of the shafts on which the respective drums are mounted.

Means 96 are also provided for each drum by which the drums may be set to offer a fixed resistance or restraint on the shaft connected therewith. Such means 96 are indicated as rods 97 fixed at one end and provided with an adjusting nut for tightening the brake bands of the drums in any desired position.

We will now describe the method and procedure followed in utilizing our improved apparatus:

In describing first the normal automatic operation of the drilling apparatus, the prime mover 11 continuously supplies power to the differential 13 through chain drive 12 tending to rotate the spider mounting the pinion gear 28. This action imposes upon the main shaft 14 and the quill shaft 21 a definite ratio of force depending upon the relative size of the gears 18 and 27. With these gears of equal size as indicated, the force tending to rotate the main shaft 14 will be equal to the force tending to rotate the quill shaft 21. The force tending to rotate the quill shaft 21 is made to pass through the chain drive 60 and the chain drive 61 to the rotary table 10, by bringing the clutch 45, through manipulation of lever 83, into position so that the sprocket wheel 42 is driven by the quill shaft 21.

The force applied to the main shaft 14 is utilized to exert a lifting force upon the drill stem in order to govern the feed pressure which is applied to the bit. In operation, the weight of the drill stem exerts a force through line 6 upon the drawworks tending to unreel the line and permit the drill stem 8 to lower. By selective utilization of the chain drive connections between the main shaft and the drawworks, this force can be opposed by various forces originating from the prime mover 11. It will be readily understood that whenever the force applied to the drawworks tending to lift the drill stem is in balance with the contrary force supplied by the weight of the drill stem, the hoisting apparatus will be in equilibrium and the main shaft 14 held stationary. With any definite set speed ratio between the main shaft 14 and hoisting drum 7, the apparatus will automatically bring itself to a state of equilibrium when the force due to the suspended weight of the drill stem is equal to the force applied by the prime mover tending to lift the drill stem. The magnitude of the lifting force is thus determined by the selection of the speed ratio between the main shaft 14 and the hoisting

drum 7. Since, as before pointed out, the lifting force applied by the main shaft 14 of the differential is equal to the rotating force applied to the quill shaft 21, the resultant torque applied to the drill stem is likewise determined by the selection of the speed ratio between the main shaft 14 and the hoisting drum 7.

It is necessary, in an apparatus of this character to provide means for producing various changes in speed ratios between the hoisting drum 7 and the main shaft 14 for the reason that in drilling operations different types of bits are employed or different characters of formation drilled upon may require a different feeding pressure upon the bits, and moreover, as the hole is progressively lengthened due to the increase in weight of the lengthened drill stem, it is necessary to but apply increased lifting forces upon the drill stem if the same feeding pressure or torque is to be maintained.

The employment of the line shaft 56 and the use of such line shaft as a countershaft for providing a plurality of selectively utilizable chain drives between the main shaft 14 and the drum 7 not only allows their speed ratio to be varied, but accomplishes this purpose without expensive modifications in the present form of drilling apparatus. It also accomplishes such variation in speed ratio with apparatus compact in form and of the character of drive connection which has been found best suited for the work, due to the inherent slack in the chains to withstand the shocks of drilling operations.

It will be readily apparent that the drilling apparatus once set in operation maintains upon the drill stem a definite torque with continual increase or decrease of the feeding pressure applied to the bit as the different conditions of drilling require, the feed of the drill stem being entirely automatic.

It will also be apparent that the purpose and mode of operation of the chain drive between the main shaft 14, line shaft 56, and the chain drives between the line shaft 56 and hoisting drum 7, do not require the clutches for selectively setting in action the different chain drives to be located in any particular place. Thus the clutches for the chain drive between the line shaft 56 and drum 7 might be placed upon the line shaft 56 instead of on the drum 7, and the clutches for the chain drives between the main shaft 14 and the line shaft 56 might be placed upon the line shaft instead of upon the main shaft 14. The invention includes, of course, all such obvious modifications.

If the number of change speed chain drives in the apparatus does not give all the desired variations in the lifting force to be applied to the drill stem or the torque to be applied to the drill stem, the brake drums 54 and 55 provide a supplemental means for this control.

The brake drum 54 on the main shaft 14 may be utilized to apply a progressively increasing resistance to the rotation of the main shaft corresponding to a greater weight applied by the drill stem. The use of this drum is of special value in the early stages of the drilling, when, due to the fact that the drill stem is of insufficient weight, it is not able to balance the rotating force required to impose a desired torque on the drill stem. The drum 54 may be operated by either the handles 95 or the set control means 96. Preferably for this operation the set control means should be utilized to free the apparatus from any dependence upon the skill of the operator.

The drum 54 on the main shaft 14 can also be utilized when the selective chain drives will not place the desired torque upon the drill stem, due to the reason that in one selective arrangement a lower torque than is desired is obtained, and in the next selective arrangement a higher torque than is desired is obtained. By employing that arrangement which gives a lower torque than is desired and placing additional restraint upon the main shaft 14 by the brake drum 54, any desired torque can be obtained.

The brake drum 55 upon the quill shaft 21 may be employed when spudding is desired or any other operation in which it is desired to lift the drill stem or to remove feed pressure therefrom without permitting the rotary table to speed up or when it is desired to lift the drill stem and stop the rotation of the rotary table without disengaging the chain drives. This brake 55 acts by imposing an additional resistance to the rotation of the quill shaft which increases the force applied through the main shaft 14 to lift the drill stem. Also by this arrangement of apparatus we are enabled to perform an operation novel in the drilling of wells, that is, stop the rotation of the drill stem by a manually controlled device and without shutting down the prime mover 11 or without disengaging the prime mover 11 from a driving engagement with the rotary table.

The quill clutch 41 keyed to the main shaft 14 engageable with the quill shaft 21 to lock these shafts rigidly together provides a means for proper manipulation of the hoisting drum 7 when it is desired to hoist the drill stem from the hole. When it is desired to lift the drill stem without rotating it the quill clutch is brought into engagement with the quill shaft, as shown, and the clutch 45 connecting the sprocket wheel 42 with the quill shaft 21 is disengaged by means of the lever 83. In this case the entire power and force of the prime mover is applied to lift the drill stem. It is obvious that in performing this service of lifting the drill stem, that if instead of locking the quill shaft and main shaft together by the clutch 125

41, the main driving sprocket 42 be left in engagement with the quill shaft but held firmly against rotation by the brake 55, an additional speed ratio may be obtained between the prime mover 11 and the drum 7 double that by any other means.

It is also obvious that when by the use of the quill clutch 41 the differential mechanism is converted into a solid drive, it permits the 10 rotary machine to be rotated in either direction without the functioning of the differential.

While the embodiment of the invention herein described is well adapted to accomplish the purposes and objects of this invention, it is understood that various modifications may be made without departing from the spirit of the invention. This invention therefore is not limited to the specific embodiment described for the purpose of illustrating the principles of the invention, but includes all such modifications, changes, substitutions, and equivalents as come within the scope of the appended claims.

25 We claim:—

1. An apparatus for drilling wells, comprising a prime mover, a drill bit, means for rotating the drill bit, means for controlling the feed pressure on the drill bit, 30 a differential connecting the prime mover with the rotating means and feed pressure control means, the connection between the differential and feed pressure control means consisting of a plurality of chain drives selectively utilizable for establishing various speed ratios between the differential and feed pressure control means, said chain drive operating through the medium of a countershaft.

40 2. In an automatic well drilling apparatus, the combination of a hoisting drum, a rotary table, a prime mover, and a differential driven by said prime mover and having its driving shafts connected by means of chain 45 drives to the hoisting drum and rotary table respectively, the connection between the differential and hoisting drum including a plurality of selectively utilizable chain drives operative to vary the speed ratio therebetween, the chain drives operating through the medium of a countershaft, the countershaft also serving as an axle for sprockets forming part of the chain drive connection between the differential and rotary table.

50 3. In an automatic well drilling apparatus, the combination with a rotary table, a hoisting drum, and a prime mover, of a differential driven by the prime mover and having one of its driving shafts extending through the differential and provided with bearings at opposed sides of the differential gearing so as to function as a main supporting shaft, the other driving shaft being of quill form and revolvable thereon, 60 one of said driving shafts being operably

connected to the rotary table, the other driving shaft being operably connected to the hoisting drum.

4. In an automatic well drilling apparatus, the combination of a prime mover, drill stem rotating means, drill stem hoisting means, and a differential connecting the prime mover to the rotating and hoisting means, the differential having one of its driving shafts formed as a main supporting 70 shaft for the differential, and the other driving shaft formed as a quill shaft revolvable on the main shaft, said differential also having a pinion gear carrying member rigid with the housing or case rotatable about the axis of the main shaft, the housing being carried at one side by the supporting shaft, and at the other side by the quill shaft.

5. In an automatic well drilling apparatus, the combination of a prime mover, drill stem rotating means, drill stem hoisting means, and a differential operably connecting the prime mover with the rotating and hoisting means, the differential having one of its driving shafts formed as a main supporting shaft, the other driving shaft being of quill construction mounted on the supporting shaft, the pinion gears of the differential being carried by a housing and 90 revolvable about the axis of the supporting shaft, the housing providing a lubricant chamber entirely enclosing the differential gearing and in communication with the bearings between the quill shaft and main shaft 95 and the bearings between the housing, main shaft and quill shaft.

6. In an automatic well drilling apparatus, the combination of a prime mover, drill stem rotating means, drill stem hoisting means, and a differential operably connecting the prime mover with the rotating and hoisting means, the differential having one of its driving shafts formed as the main supporting shaft, the other driving shaft being of quill construction and mounted on the supporting shaft, a connection between said quill driving shaft and said drill stem rotating means, a plurality of selectively utilizable chain drive connections between the main supporting shaft and the drill stem hoisting means, including sprockets mounted upon said main shaft, and clutch means for selectively connecting said chain drive connections.

7. In an automatic well drilling apparatus, the combination of a prime mover, drill stem rotating means, drill stem hoisting means, and a differential operably connecting the prime mover with the rotating and hoisting means, the differential having one of its driven shafts formed as a main supporting shaft, the other driven shaft being of quill construction and mounted on the supporting shaft, the pinion gear of the differential being carried by a housing and revolvable about 120

the axis of the supporting shaft, and a plurality of selectively utilizable chain drive connections between the main supporting shaft and the drill stem hoisting means, said
5 chain drive connections utilizing said main shaft as a mounting for sprockets thereof, and clutch means for selectively connecting said chain drive connections.

8. In an automatic well drilling apparatus,
10 the combination of a prime mover, drill stem rotating means, drill stem hoisting means, and a differential operably connecting the prime mover and the rotating and hoisting means, the differential having one of its shafts
15 formed as a supporting shaft for the differential, the other shaft being a quill shaft revolvable thereon, the pinion gears of the differential being carried by a housing and revolvable about the axis of the supporting
20 shaft.

9. In an automatic well drilling apparatus, the combination of a prime mover, drill stem rotating means, drill stem hoisting means, and a differential operably connecting the
25 prime mover and the rotating and hoisting means, the differential having one of its shafts formed as a supporting shaft for the differential, the other shaft being a quill shaft revolvable thereon, the pinion gears of the differential being carried by a housing and revolvable about the axis of the supporting
30 shaft and the prime mover being connected to rotate the housing carrying the pinion gears.

35 Signed at Torrance, Calif., this 6th day of March, 1925, and at Toledo, Ohio, this 18th day of April, 1925, respectively.

LEWIS E. ZERBE.
MERTON T. ARCHER.
